FLUID MACHINE

Frank R. Thomas, Los Angeles, Calif.

Application February 11, 1933, Serial No. 656,226

1 Claim. (Cl. 103—162)

This invention relates to a fluid machine which may be used as a fluid motor or a fluid pump.

It is an object of this invention to produce a fluid machine which may be used as a fluid motor or pump.

A further object is to produce a fluid pump which will deliver a substantially constant flow of fluid.

A further object is to produce a fluid pump which is adaptable for pumping gaseous or liquid fluids or a fluid comprising a mixture of gases and liquid of any proportion.

A further object is to produce a fluid pump in which the fluid being pumped will flow in nearly a straight path from the inlet to the discharge end thereof.

A further object is to produce a fluid pump capable of pumping very viscous fluids.

A further object is to produce a fluid pump having valve means so arranged that the full cross sectional area of the pumping bores of the pump cylinders will be opened to the inlet passages during the greater portion of the suction phase of the pumping cycle and fully opened to the outlet passage during the discharge phase of said cycle.

Other objects and advantages of the invention will become apparent as the nature of the same is more fully understood from the following description and accompanying drawings wherein is set forth what is now considered to be a preferred embodiment. It should be understood, however, that this particular embodiment of the invention is chosen principally for the purpose of exemplification, and that variations therefrom in details of construction or arrangement of parts may accordingly be effected, and yet remain within the spirit and scope of the invention as the same is set forth in the appended claim.

40 In the drawings:

Figure 1 illustrates a side elevation of one form of the invention;

Figure 2 illustrates an enlarged sectional view taken substantially in the plane of line 2—2 of

45 Figure 1.

Figure 3 illustrates an enlarged sectional view taken substantially in the plane of line 3—3 of Figure 1.

Figure 4 illustrates an enlarged sectional view 50 of Figure 1.

In the invention illustrated in Figures 1 to 4, inclusive, a suitable housing 10 may be formed of two substantially similar portions 11 and 12 and each portion may be provided with a central bore

55 13. As may be observed from Figures 1 and 4,

the half portions with their central bores are angularly bolted together as by means of suitable flanges 14 and bolts 15. A cylinder 16 may be operatively mounted in the half portion 11 while corresponding cylinder 17 may be mounted in the half portion 12. It is preferable to provide clearance space between each cylinder and its half portion so as not to have the frictional drag of such large surfaces; however, if desired, the cylinders may be journaled in their respective casings. The cylinders may be supported by a common axle 18 having arms 19 and 20 angularly related to the same degree as that of the casing, and upon each of said arms a bearing bushing 21 may be slidably mounted but keyed against rotation as by means of key 22 acting in key way 23. Each cylinder may be journaled upon one of the bushings and, if desired, suitable anti-friction bearing may be provided. The bushings may be supported by suitable cylinder heads 24 and 25 and in turn may support the axle 18. Each bushing may be slidably mounted in its respective cylinder head and keyed against rotation as by means of key 26 and key way 27. Each cylinder head may be mounted upon the outer end of its respective casing as, for example, as illustrated in Figure 4, the cylinder head 24 may be clamped between the casing portion 11 and the inlet cover 28 by suitable bolt means 29, while the cylinder head 25 may be clamped between the casing portion 12 and the outlet cover 30 by similar bolt means 31. And each of the cylinder heads may be locked against rotation as by the keys 32 (note Figures 2, 3 and 4).

The cylinders may be provided with any desired number of bores as, for example, cylinder 16 may be provided with six bores 33 while cylinder 17 may be provided with a like number of bores 34, which bores are arranged parallel to the axial center of their respective cylinders, and for convenience may be referred to as the opposed cylinder bores. Due to the angular relation of the cylinders, the opposed cylinder bores are likewise angularly related.

A piston means 35 may be slidably and rotatably mounted in each set of opposed cylinder bores and each piston may be of such size as to form a close working fit with its respective bores so as to form an effective fluid seal therewith. If preferred, each end of each piston may be provided with piston rings or other common means for effectively sealing the pistons in the bores. Each piston may be provided with a fluid passage 36 of relatively large size for forming a means of

communication between the opposed cylinder bores.

A relative movement of the pistons along the cylinder bores is effected during the rotation of the cylinders due to the angularity of the two portions of the machine. The greater the angularity, the greater will be the relative motion or stroke of the pistons. However, as may be noted, the pistons do not act as pistons or plungers of the ordinary type of pump due to the passage therethrough but do act as an operative fluid sealing and conveying means between each set of opposed cylinder bores. The pumping action is due to the change in effective length of the fluid passage formed by the opposed bores and pistons. It may be noted in Figure 4 that each end of the upper piston has moved a considerable distance from the adjacent faces of the cylinder heads while each end of the lower piston closely approaches the adjacent faces of the cylinder heads. Thus the length of the fluid passage when the opposed bores are in the upper position is longer by the distance equal to the amount the piston ends have moved away from the cylinder heads. This distance is gradually reduced until finally the piston arrives at the lower position whereat the ends of the piston have moved into close proximity to the cylinder heads. And, therefore, during downward travel of each piston the fluid passage is reduced in length, thereby displacing an amount of fluid substantially equal to the difference in length of the fluid passage. During the upward travel of the pistons, the fluid passage is lengthened until the pistons return to the upper position so, therefore, fluid will be drawn into the fluid passage in proportion to its increase in length.

Valve means may be provided for permitting fluid to flow into the passages during only their upward movement and other valve means may be provided for permitting only the fluid displaced by the shortening of the fluid passage during the downward travel of the pistons to discharge therefrom.

The inlet valve means may be provided for the bores 33 of cylinder 16 which may include the cylinder head 24 in which an inlet port 37 (note Figure 2) may be provided and so arranged as to fully uncover the cylinder bores 33 during the upward movement of the passages, thus providing an unobstructed opening through which the fluid may freely flow into the cylinder bores. The cylinder head 24 may be arranged to form a close working fit with the valve end of cylinder 16 so as to effectively seal bores 33 during the downward movement thereof. Correspondingly, the cylinder head 25 may be provided with a discharge port 38 (note Figure 3) arranged to fully uncover the cylinder bores 34 during downward movement thereof and thereby to provide an unobstructed opening through which the fluid may be forced out during the shortening of the passages. The cylinder head 25 may be likewise arranged to form a close working fit with the valve end of cylinder 17 so as to effectively seal the cylinder bores 34 during the upward movement of the passages during which time the passages are opened by the port 37 for admission of the fluid being pumped. Should the direction of rotation be reversed, the inlet valve will become the discharge valve while the discharge valve will become the inlet valve and the direction of fluid flow will also be reversed.

The valve or cylinder heads 24 and 25 may be fixedly mounted in the casing and, therefore, it

may be desirable to provide means for maintaining each cylinder in close working relation with their respective cylinder heads, irrespective of expansion or contraction of the casing. Such means may include providing each bushing 21 with an outwardly projecting radial flange 39 against which the piston end of its respective cylinder may rotate. If desired, an anti-friction thrust bearing may be provided between the flanges and cylinders, while the opposite end of each bushing may be screw threaded as at 40 to receive a pair of lock nuts 41 for retaining a flanged washer 42 in predetermined relation with respect to its adjacent cylinder head and a suitable spring means 43 may be mounted upon each bushing and positioned between the washer and cylinder head. It should be remembered that each bushing is slidably mounted through its cylinder head and, therefore, each spring means is free to yieldingly retain its respective cylinder in close working relation with its respective cylinder head. Should it be desired, the spring 43 may be removed from each bushing and each washer 42 brought into direct contact with its respective cylinder head so as to firmly retain each cylinder 25 in a close working relation with its respective cylinder head. This latter may be the preferred arrangement when relatively high pressures are to be pumped.

It is desirable to provide means for simultaneously rotating the cylinders. Many different forms of drive means may be provided. The drive means illustrated in Figures 1 to 4, inclusive, may include providing each casing portion with a suitable gear housing 44 and 45, each having a projecting boss 46 and 47 arranged to abut against each other and a suitable fluid sealing means 48 may be provided to prevent fluid leakage therefrom. The bosses may also act as suitable bearings for the drive shaft 49, which shaft may extend through each of said housings. The gear housing 44 may have a suitable cover 50 fastened thereto as by means of the cap screws 51 and cover 50 may be provided with a closed bearing boss 52 for supporting the short end of the drive shaft. While the gear housing 45 may be provided with a suitable cover 53 fastened thereto as by means of cap screws 54 and cover 53 may be provided with a suitable stuffing, through which the long or drive end of shaft 48 may extend. A drive gear 55 may be suitably mounted upon shaft 48 within housing 44 while a similar gear 56 may be suitably mounted upon shaft 49 within housing 45. The cylinder 16 may be provided with a suitable gear 57 arranged to mesh with gear 55 while cylinder 17 may be provided with gear 58 arranged to mesh with gear 56. By this arrangement, each cylinder will be independently driven so as to remove any driving or binding strain from the pistons.

It may be desirable to maintain casing 10 under the inlet pressure and, therefore, a port 59 may be formed through the cylinder head 24 so as to communicate with the bore 13 of the casing and also a duct means 60 may be provided to convey inlet pressure to the two gear housings 44 and 45.

The inlet cover 28 may be provided with an inlet pipe 61 while the outlet cover 30 may be provided with a discharge pipe 62.

In the operation of the fluid machine illustrated in Figures 1 to 4, inclusive, as a fluid pump, the inlet pipe 61 may be communicated with a suitable source of fluid supply and the outlet pipe 62 arranged to conduct the discharge fluid from the machine. A source of power is connected to

the drive shaft 49 for rotating the cylinders in a direction so that the bores 33 of cylinder 16 will communicate with the inlet port 37 during the upward movement of the pistons whereby, as the pumping passage increases in length, the fluid will be drawn into the passage. And during the downward travel of the pistons the bores 33 are effectively sealed by the cylinder head 24 but the cylinder bores 34 are in communication with the discharge port 38 of cylinder head 25, thus permitting the excess fluid to be displaced as the passages are shortened. Should the direction of rotation of the cylinders be reversed, the flow of fluid will also be reversed; in other words, the invention is a truly reversible pump which may be of considerable advantage in certain chemical or distilling processes. And also due to the free unobstructed passages throughout the entire ma-

chine, relatively heavy viscous fluid may be successfully pumped.

It is to be understood that the invention is not to be limited to the details herein set forth for the sake of illustration, but is of the full scope of the following claims:

I claim:

In a fluid pump, a casing, a pair of angularly related cylinders operatively mounted in the casing, each having a plurality of bores, a hollow piston means operatively mounted in each pair of opposed cylinder bores to form a means of communication between said bores, an inlet valve means operatively associated with one of said cylinders, a discharge valve means operatively associated with the other of said cylinders, and a drive means for simultaneously and independently rotating each of said cylinders.

FRANK R. THOMAS.
